UNITED STATES PATENT OFFICE.

ROBERT B. CARSLEY, OF NEW BEDFORD, MASSACHUSETTS, ASSIGNOR TO
THE TRIUMPH HEAT AND LIGHT COMPANY, OF PORTLAND, MAINE.

VAPORIZER.

SPECIFICATION forming part of Letters Patent No. 397,631, dated February 12, 1889.

Application filed May 22, 1888. Serial No. 274,660. (No model.)

To all whom it may concern:

Be it known that I, ROBERT B. CARSLEY, of New Bedford, in the county of Bristol and State of Massachusetts, have invented an Improvement in Vaporizers, of which the following description, in connection with the accompanying drawings, is a specification, like letters on the drawings representing like parts.

10. This invention has for its object to provide apparatus in which gasoline and analogous hydrocarbons may be vaporized, and the vapor, either alone or mixed with air or gas, be employed for lighting and heating purposes.

15. My invention in a vaporizer consists, essentially, of a vessel provided with a liquid-inlet and a vapor-outlet, combined with a series of substantially - vertical double partitions forming vapor - ways, and arranged

20. within said vessel to form chambers, absorbent material in said chambers, and a plate or wall to support said double partitions, the said plate or wall forming, with the bottom of the vessel, a vapor - receiving chamber, substantially as will be described.

25. The specific features of my invention will now be more fully pointed out, and claimed at the end of this specification.

Figure 1 is a front elevation of a vaporizer 30 embodying my invention, the front plate or side being removed, and only one chamber being shown full of absorbent material. Fig. 2 is a sectional plan view of the vaporizer on line x x' , Fig. 1, with the supports or shelves for the absorbent material omitted to avoid confusion in the drawing. Fig. 3 is a section of the vaporizer on line x' x' , Fig. 2. Fig. 4 is a detail of one of the supports or shelves; and Fig. 5 is a vertical section, on a large scale, 40 of an automatic valve, to be referred to.

The vessel A, preferably of tin, and which may be of any desired shape, being herein shown as oblong, is divided into a series of chambers or spaces, a , by double partitions a' , composed, preferably, of wire-netting or other foraminous material, bent or folded upon itself to form a vapor way or passage. The double partitions a' are supported above the bottom of the vessel by a plate or wall, a^2 , 45 preferably of wire-netting, the said plate or wall forming, with the bottom of the vessel A,

a chamber, b , communicating with the vapor ways or passages a , the vapor descending from the said ways or passages a into the chamber b .

The chambers or spaces a contain asbestos or other absorbent material, b' , which is preferably supported by detachable shelves or supports b^2 , (shown separately in Fig. 4,) there being preferably two or more superimposed shelves in each chamber, as shown in Fig. 1, the said shelves preventing the absorbent material becoming matted or packed together when saturated with gasoline or analogous hydrocarbon to be vaporized.

The gasoline or analogous hydrocarbon is supplied through a suitable pipe, b^3 , herein shown in the side of the vessel A, the said pipe being provided with a suitable cap, b^4 , the said vessel being turned on its side when 70 it is to be filled, the liquid hydrocarbon preferably flowing from the pipe b^3 upon a distributing - plate, b^5 , preferably soldered or otherwise attached to one of the double walls, a' , a more even distribution of the liquid hydrocarbon being thus obtained.

The double partitions a' are preferably strengthened, as herein shown, by braces c , composed, preferably, of tin bent or shaped substantially as shown in Fig. 3 and soldered 80 or otherwise fastened to the double partitions, the said braces being especially effective when the double partitions are made of wire - netting to prevent crushing together of the said partitions, thus maintaining the vapor ways 85 or passages free and unobstructed.

The central chamber or space contains, as herein shown, an inverted trough or cap, c^2 , preferably extended the width of the vessel A, the said trough or cap being supported, as 90 shown, by the plate or wall a^2 .

The vapor generated in the vessel A is conveyed therefrom by a discharge-pipe, d , extended up into the trough or cap c^2 and connected in practice to a burner - pipe, (not 95 shown,) the discharge-pipe being provided with a suitable cock or valve. (Not shown.)

The vessel A has secured to its top an automatic valve comprising a valve case or shell, d' , (see Figs. 1 and 5,) herein shown as provided with a conical base, which is soldered 100 or otherwise secured to the top of the vessel,

the said base forming the seat for a valve, d^2 , having its stem d^3 extended through guides d^4 and threaded at its end to be engaged by a nut, d^5 , the said valve-stem being encircled 5 between one of the guides d^4 and the nut d^5 by a coiled spring, d^7 , the tension of which may be regulated to just seat the valve d^2 —that is, to substantially balance the said valve. The valve-shell is provided with a cap, d^8 , 10 which covers the valve when the apparatus is being transported, but which is removed when the apparatus is set up in operative position.

In operation, the cock or valve in the discharge-pipe being closed, the vessel A is turned 15 on its end and the gasoline admitted through the pipe b^3 (the cap b^4 being removed) until the absorbent material has been saturated. The cap b^4 is then replaced and the vessel 20 turned into operative position, (shown in Fig. 1,) and any excess or surplus liquid may be drawn off by the drip-cock e , if desired. The gasoline immediately begins to give off vapor, which passes into the vapor ways or passages, 25 and, being heavier than air, descends by gravity into the chamber b , from which it passes up into the trough and out by the discharge-pipe, the said trough being extended the width of the vessel, thus affording a greater head, as 30 it were, and thereby a better and freer flow of vapor to the burners when the cock in the discharge-pipe is opened. When the absorbent material is saturated, the vapor generated in the vessel A exerts a pressure upon the 35 valve d^2 and assists to seat the same, thereby preventing escape of vapor from the vessel A. When the cock at the burner is opened, the pressure upon the valve is relieved, and the said valve is opened by atmospheric pressure, 40 the air entering the vessel A and acting to expel all or substantially all the vapor therein.

I have herein described my improved apparatus as a vaporizer; but it is evident it may also be used as a carbureter to enrich 45 air or other gas which may be admitted into the said vessel through the valve, a suitable pipe connected to the gas-supply or to a reservoir containing compressed air, and not herein shown, being connected to the valve-shell.

It will be noticed that the double partitions are secured in the vessel in a substantially vertical position to afford a free and unobstructed passage for the vapor.

I claim—

1. In a vaporizer, the combination, with a vessel provided with a liquid-inlet and a vapor-outlet, of a series of substantially-vertical double partitions forming vapor-ways and arranged within said vessel to form chambers, 60 absorbent material in said chambers, and a plate or wall to support said double partitions, the said plate or wall forming, with the bottom of the vessel, a vapor-receiving chamber, substantially as described. 65

2. In a vaporizer, the combination, with a vessel provided with a liquid-inlet and a vapor-outlet, of a series of double partitions forming vapor-ways, and arranged within said vessel to form chambers, absorbent material 70 in said chambers, a plate or wall to support said double partitions, and shelves b^2 to support the absorbent material, substantially as described.

3. In a vaporizer, the combination, with a vessel provided with a liquid-inlet and a vapor-outlet, of a series of double partitions forming vapor-ways, and arranged within said vessel to form chambers, absorbent material 80 in said chambers, a plate or wall to support said double partitions, and shelves to support the absorbent material, and an inverted trough or cap located above the outlet-pipe of the vessel, substantially as described. 75

4. In a vaporizer, the combination, with a vessel provided with a liquid-inlet and a vapor-outlet, of a series of double partitions forming vapor-ways, and arranged within said vessel to form chambers, absorbent material in said chambers, a plate or wall to support said 90 double partitions, and shelves to support the absorbent material, and an inverted trough or cap located above the outlet-pipe of the vessel, and a check-valve secured to the top of the vessel and adapted to open to admit air 95 to the vessel when the vapor is being withdrawn from the said vessel, substantially as described.

In testimony whereof I have signed my name to this specification in the presence of 100 two subscribing witnesses.

R. B. CARSLEY.
